(57) **CLAIM**

The ornamental design for the wheel cap, as shown and described.

DESCRIPTION

FIG. 1 is a perspective view of the wheel cap showing my new design;

FIG. 2 is a front elevational view thereof;

FIG. 3 is a cross-sectional view taken along the line 3-3 of FIG. 2; and,

FIG. 4 is a cross-sectional view taken along the line 4-4 of FIG. 2.

The broken lines showing the environment are for illustrative purposes only and form no part of the claimed design.

1 Claim, 4 Drawing Sheets

FIG. 1

FIG. 2

FIG. 3
